UNITED STATES PATENT OFFICE.

EDMUND P. KINNE, OF ALLIANCE, OHIO, ASSIGNOR TO AMERICAN STEEL FOUNDRIES,
OF CHICAGO, ILLINOIS, A CORPORATION OF NEW JERSEY.

COUPLER.

Application filed October 5, 1922. Serial No. 592,520.

To all whom it may concern:

Be it known that I, EDMUND P. KINNE, a citizen of the United States, residing at Alliance, in the county of Stark and State 5 of Ohio, have invented certain new and useful Improvements in Couplers, of which the following is a specification.

This invention relates to couplers.

Couplers are subjected to excessive 10 strains, especially under severe service conditions. As a result of actual service conditions and also experiments, it is found under severe conditions that when the coupler is subjected to high compressive forces that 15 the shank thereof shows a definite set and a reduction in the length of the key-hole longitudinally of the shank. The set and reduction in length of the key hole in certain instances has made it impossible to apply 20 or withdraw a standard key with respect to said hole.

Accordingly, one object of the invention is to improve the design of the shank of what is known as the standard type D coupler in a manner to reduce the set therein and to prevent reduction in the length of the key-hole under excessively high compressive forces.

Another object is to provide a simple, durable 30 and efficient coupler shank adapted to meet the various requirements under service conditions.

These and other objects are accomplished by means of the arrangement disclosed on 35 the accompanying sheet of drawings, in which—

Figure 1 is a top plan view of a coupler, parts being shown in section, embodying my invention;

Figure 2 is a side elevation of the same 40 coupler, parts being shown in section; and

Figure 3 is a sectional view taken in the plane of line 3—3 of Figure 2.

The various novel features of the invention will be apparent from the following 45 description and drawings and will be particularly pointed out in the appended claims.

Referring to the figures of the drawings, it will be noted that the invention is illustrated in connection with what is known as 50 the standard type D coupler, having a head 10 and shank 11. It will be noted that the shank is hollow and is provided with upper and lower walls 12 and 13 respectively, 55 and side walls 14. The rear wall 15 of the

shank is provided with an opening 16 for facilitating the molding of the shank and for reducing the total weight thereof. In this particular instance the coupler is provided with a transversely horizontally arranged key-hole 17 for the reception of a standard key for making the usual connection between the coupler shank and another part or parts of the draft mechanism.

As mentioned hereinabove, it has been established, as a result of actual extreme service conditions, and also as a result of experiment, that the shank shows a definite set and that the key-hole 17 has been reduced in length longitudinally of the shank 60 under excessively high compressive forces. Under extreme cases it has been found that this distortion has been sufficiently extensive to make it impossible to apply or withdraw a standard key with respect to the key-hole. 70

To overcome this set in the shank and to prevent a reduction of the key-hole longitudinally of the shank, the design of the shank has been improved. This improvement includes the provision of a wall 18 of 80 metal entirely surrounding the key-hole 17 throughout the transverse length thereof and connecting the upper and lower portions of said wall with the upper and lower outer walls 12 and 13 respectively of the 85 shank by means of integrally formed reinforcing pillars or portions 19. Preferably the reinforcing pillars 19 are arranged midway between the side walls of the coupler shank and adjacent the ends of the key-hole 90 longitudinally of the shank, associated pillars 19 preferably being in vertical alignment. The front and rear portions of the wall 18 are increased in thickness from the center of the shank toward the side walls 14 95 thereof, as shown particularly in Figure 1.

It is my intention to cover all modifications of the invention falling within the spirit and scope of the following claims.

I claim:

1. A coupler having a hollow shank with a key-hole therein, there being a wall of metal entirely surrounding the key-hole, and a plurality of reinforcing portions extending in the same direction between said 105 wall and the opposite outer walls of the shank for reducing the set therein and preventing reduction in the length of the key-hole longitudinally of the shank under compressive forces.

100

110

2. A coupler having a hollow shank with a transverse key-hole therein, there being a wall of metal entirely surrounding the key-hole, and vertical reinforcing portions extending between said wall and the upper and lower outer walls of the shank for reducing the set therein and preventing reduction of the length of the key-hole longitudinally of the shank under compressive forces.
- 5 3. A coupler having a hollow shank with a transversely extending key-hole therein, there being a wall of metal surrounding the key-hole, and vertically aligned reinforcing portions extending between said wall and outer walls of said shank for reducing the set therein and preventing reduction in the length of the key-hole longitudinally of the shank under compressive forces.
- 10

Signed at Alliance, Ohio, this 30th day of September, 1922.

EDMUND P. KINNE.
